(57) **CLAIM**

The ornamental design for a watercraft as shown and described.

DESCRIPTION

FIG. 1 is a front perspective view of a watercraft incorporating the new design;

FIG. 2 is a back perspective view thereof;

FIG. 3 is a front view thereof;

FIG. 4 is a back view thereof;

FIG. 5 is a right side view thereof;

FIG. 6 is a top view thereof; and,

FIG. 7 is a bottom view thereof.

The broken lines illustrate portions of the watercraft that form no part of the claimed design.
